UNITED STATES PATENT OFFICE.

MARY V. KAVANAGH, OF NEW YORK, N. Y., ASSIGNOR TO THE BUTTERICK PUBLISHING COMPANY, (LIMITED,) OF SAME PLACE.

DESIGN FOR A LADY'S COAT.

SPECIFICATION forming part of Design No. 18,216, dated March 27, 1868.

Application filed February 23, 1868. Serial No. 265,051. Term of patent 3½ years.

To all whom it may concern:

Be it known that I, MARY V. KAVANAGH, of the city, county, and State of New York, have invented and produced a new and original Design for a Pattern of a Lady's Coat; and I do hereby declare that the engraved prints accompanying this specification convey to any one accustomed to using paper patterns a clear understanding of how a garment made up by the pattern will appear.

The design shows loose fronts exhibiting shirrings at the neck and opening all the way down over a narrow vest that displays a closing at its center; a close-fitting back, from

which depends a triple box-plaited skirt; 15 pocket-welts on the hips; bell sleeves, and a standing collar with a pointed overlapping end.

What I claim as my invention, and desire to secure by Letters Patent, is—

The design for a lady's coat, as shown in the engraved prints accompanying this specification.

M. V. KAVANAGH.
